UNITED STATES PATENT OFFICE.

GEORGE MÁRKUS, OF STONEGA, VIRGINIA.

BEDSTEAD.

1,008,168.

Specification of Letters Patent. Patented Nov. 7, 1911.

Application filed March 20, 1911. Serial No. 615,637.

To all whom it may concern:

Be it known that I, GEORGE MÁRKUS, a subject of the King of Hungary, residing at Stonega, in the county of Wise and State 5 of Virginia, have invented certain new and useful Improvements in Bedsteads, of which the following is a specification, reference being had therein to the accompanying drawing.

10 This invention relates to bedsteads, more particularly to the side rails thereof and has for its object to provide side rails for bedsteads in a manner as hereinafter set forth capable of having the length thereof increased or diminished when occasion so requires, thereby providing for different 15 lengths of beds.

Further objects of the invention are to provide an extensible side rail for bedsteads 20 which is simple in its construction and arrangement, strong, durable, efficient in its use, conveniently adjusted to increase or diminish the length thereof, readily set up with respect to the other elements of the 25 bedstead, and comparatively inexpensive to manufacture.

With the foregoing and other objects in view, the invention consists of the novel construction, combination, and arrangement of 30 parts as hereinafter more specifically described and illustrated in the accompanying drawings wherein is shown the preferred embodiment of the invention but it is to be understood that changes, variations and 35 modifications can be resorted to which come within the scope of the claim hereunto appended.

In the drawings wherein like reference characters denote corresponding parts 40 throughout the several views: Figure 1 is a perspective view of a portion of a bedstead showing the adaptation therewith of a side rail in accordance with this invention, the rail being broken away at one end. Fig. 2 is a longitudinal sectional view of a side rail in accordance with this invention, the rail being extended and broken away at one end. Fig. 3 is a section on line III—III, Fig. 2, looking in the direction of the arrow. Fig. 4 is a section on line IV—IV, Fig. 2, looking in the direction of the arrow. Fig. 5 is a perspective view of one of the sections of the rail. Fig. 6 is a perspective view of a shiftable coupling device for the 55 sections of the rail, and, Fig. 7 is a perspec-

tive view of the other section of the rail, said section being broken away.

Referring to the drawings in detail, 2 denotes a bed post through which is detachably connected in a known manner the section A 60 of the side rail, the other section of the side rail is indicated by the reference character B. The section A is of less length than the section B and extends into and is shiftable with respect to the said section B. 65

The bed rail is formed of the two sections A and B, the section A being formed with what may be termed a head 4 at one end of a rectangular body-portion 4^a. The head 4 is of greater width than the body portion 4^a 70 and of greater height than said body-portion 4^a, but the top of the head 4 is flush with the top of the body-portion 4^a. That end of the body-portion 4^a which merges into the head 4 is formed with a relatively long vertically 75 disposed longitudinally-extending slot 5 and each side 4^b of the body-portion 4^a, approximately centrally of the side has an integral V-shaped ridge 6 which extends longitudinally and is of the same length as the length 80 of the body-portion 4^a.

The section B is adapted to be secured to the opposite bed post in a known manner and comprises a relatively long rectangular body-portion 1 formed at one end with a 85 longitudinally-extending recess 8 having each of the side walls thereof provided with a longitudinally-extending V-shaped guide groove 7 which is of the same contour as the ribs 6 of the body-portion 4^a. The recess 8 90 is adapted to receive the body-portion 4^a and is of the same length as the body-portion 4^a. The grooves 7 are for the reception of the ribs 6 and constitute not only a guiding means for the ribs but also means to prevent vertical movement of the body-portion 4^a with respect to the body-portion 1 of the section B. 95

The recess 8 is of less depth than the depth of the body-portion 1, but of greater 100 height than the height of the body-portion 4^a and arranged within said groove is a shiftable locking plate 2 formed at each end with a screw-threaded aperture 2^a. One end of the locking plate 2 is detachably-connected with the body-portion 4^a through the medium of a headed bolt 3, the latter extending through the slot 5. The other end of the locking member 2 is detachably connected with the body-portion 1 by a headed screw 110

11. A clearance is provided for the shank of the screw 11 by a slot 10 in the bottom wall of the recess 8.

By loosening the screw or bolt 3 the body-portion 4^a can be shifted with respect to the recess 8 thereby decreasing or increasing the length of the rail. The body-portion 4^a together with the locking plate 2 can be positioned within the recess 8 by adjusting the screw or bolt 11. When the locking piece 2 and body-portion 4^a are positioned within the recess 8, the head 4 abuts against the end of the body-portion 1. By tightening the bolts or screws 3 and 11 when the body-portion 4^a and locking piece 2 are positioned within the recess 8, the section B is prevented from shifting with respect to the section A or vice versa.

What I claim is:

20 An extensible side rail for bedsteads comprising a long and a short section, said long section having its upper face provided with a recess with the side walls thereof formed with longitudinally extending guide grooves,

a coupling plate connected to said recessed section and capable of being shifted outwardly with respect to said section, said short section including a body portion and a head, said body portion having laterally guide ribs engaging in said grooves, said body portion and said long section each formed with a longitudinally extending slot, means extending through the slot of the long section and engaging with the coupling plate for connecting one end thereof in position, and means extending through said body portion and engaging with the other end of the coupling plate for adjustably connecting the plate to the body portion, said body portion mounted upon the coupling plate and extending in said recess.

In testimony whereof I affix my signature in the presence of two witnesses.

GEORGE MÁRKUS.
